UNITED STATES PATENT OFFICE

WALTER H. COLES AND BERT J. NELSON, OF TROY, OHIO, ASSIGNORS TO THE SKINNER
IRRIGATION COMPANY, OF TROY, OHIO, A CORPORATION OF OHIO

SPRINKLER

Application filed April 25, 1930. Serial No. 447,347.

This invention relates to sprinkling or irrigating apparatus and particularly to sprinklers having a sprinkling member adapted to be slowly rotated while in operation.

One object of the invention is the provision of a sprinkler of this character, of the pop-up type, having a supporting housing portion from which the various supported parts of the sprinkler may be readily removed to provide access to the interior of the housing portion for cleaning purposes or the like.

Another object of the invention is the provision of a sprinkler having a supporting housing portion extending substantially to the top of the sprinkler and within which the sprinkler member is normally retracted, the top of the supporting housing being a separate housing piece detachably connected to the top of the supporting housing portion by means accessible at the top of the sprinkler.

Other objects and advantages of the invention will be apparent from the following description, the appended claims, and the accompanying drawing, which discloses two embodiments of the invention, and in which:—

Fig. 1 is a vertical section through a sprinkler embodying the present invention;

Fig. 2 is a horizontal section on the line 2—2 of Fig. 1;

Fig. 3 is a section on the line 3—3 of Fig. 2; and

Fig. 4 is a vertical section through a sprinkler showing a modified form of construction.

In the drawing, in which like characters of reference designate like parts in the various views, and referring first to Figs. 1 to 3 inclusive, the sprinkler herein shown is of the pop-up type in which the sprinkling member is adapted to be raised to an extended operating position when in operation. When not operating the sprinkling member is housed substantially flush with the top of a housing, designated generally 10, which is buried in the ground so that its top is substantially flush with the ground level. The sprinkling member designated generally 11 comprises a sprinkling cap 12 which seats in a depression

13 in the housing when the sprinkler is not in operation. Below this cap 12 are any suitable number of sprinkling nozzles 14 which are in communication with the water passage 15 provided in the sprinkling member.

The sprinkling member embodies a tubular portion 16 which is rotatably mounted and supported by a bearing portion 17 provided in the housing top piece 18. A socket 19 in this top piece provides a recess in which the operating parts of the sprinkling member may be retracted and enclosed. The top of this housing piece 18 is so arranged that it is flush with the ground level so that when the sprinkler is not in operation there will be no obstructions projecting above the ground level and the sprinkler will be practically invisible.

Detachably connected to the top piece 18 is a supporting housing portion 20, of substantially cup shape. At the lower end of this portion 20 is a threaded water inlet passage 21 to which the water supplying pipe may be attached. The upper end of the housing portion 20 is preferably flanged outwardly as indicated at 22, and suitable screws 23 or the like detachably connect the top of the housing portion to the top housing piece 18, a suitable washer 24 being employed to make the joint water-tight. These screws are accessible from the top of the sprinkler so that the top piece 18 may be disconnected from the housing portion 20 without disturbing the ground around the sprinkler.

Above the water inlet opening 21 is a partition or wall 26 having water inlet passages 27 and 28 so that water flowing into the housing portion 20, in the space 29, may flow through these openings 27 and 28 into a water chamber 30. This partition wall is removably supported within the supporting housing portion and may be detachably joined to it directly, but as shown the wall 26 forms a part of a separate water chamber within the housing portion. The sides of the water chamber 30 are provided preferably by a tube 31 of brass or the like, the lower end of this tube being threaded as indicated at 32 so that the wall 26 may be secured thereto. The upper end of the tube 31 is preferably se-

cured to a flange 35 provided on the top piece 18.

Within the water chamber 30 are suitable means for providing for slow rotational movements of the sprinkling member, operated by the passage of water through the water chamber as the water flows up through the inlet openings 27 and 28 and then out through the tube 16 and the holes through the sprinkling nozzles. Preferably this means comprises a rotatable member 37 which is rotated rather rapidly as the water flows up through the water chamber. The water is given a rotational or whirling movement, as it enters the water chamber, as the inlet openings 27 and 28 are so inclined, as shown in Figs. 2 and 3, that the water must rotate about a central vertical axis. This rotational movement of the water rotates the member 37, which is journaled on a depending stud 38 connected by the arms 39 to the lower end of the tube 16. These arms 39 support a lobe like half ring portion 40, which is rigidly connected to the arms and which projects out somewhat in the nature of a cam, being eccentrically curved with reference to the vertical axis of rotation. This ring 40 is struck by a momentum or impact member 41 having an upstanding impacting arm 42, and a horizontal surface 43, the latter being slidably mounted on the rotatable member 37 and adapted to rotate therewith. A weighted end 44 normally tends to hold the impact member out towards the left as viewed in Fig. 1, during operation, so that the upstanding arm 42 strikes against the cam ring 40 each time the rotatable member 37 revolves through one revolution. The impact member 41, however, may slide towards the right, an elongated slot 45 being provided for this purpose, so that it may pass by the projecting part of the ring 40. Thus the impact member 41 is rather rapidly rotated due to the passage of the whirling water, and impacts are thus imparted to the rotatable sprinkling member to move it slowly step by step and thus cause the water to be distributed to all sides of the sprinkler.

In accordance with an arrangement of parts as above described, it is apparent that any dirt that may be collected below the partition or wall 26 may be readily cleaned out without disconnecting the entire sprinkler, by merely removing the fastening screws 23 and withdrawing the top piece 18 and the parts connected to it, the partition 26 and the entire water casing providing the water chamber 30 being withdrawn through the top of the housing portion.

Another form of the invention is shown in Fig. 4. In this form of construction the water casing within the water housing is rotatable with the sprinkling member. The housing embodies the top piece 50 detachably connected by the screws 51 to the cup-shaped

supporting housing 52. The rotatable sprinkling member 53 is formed at its upper end substantially like the sprinkling member 11 previously described. The lower end of the sprinkling member, however, forms the top wall 55 of the water casing 56 which provides the water chamber 57 within the supporting housing portion 52. The sides of this water casing are preferably formed by a cylindrical tube 58 which is attached by screw threads 59 to the top casing wall 55 and by screw threads 60 to the lower wall or partition 61. This lower wall 61 is provided with inclined inlet openings 62 and 63 to impart a rotational whirl to the water in the water chamber 57. Within the water chamber 57 is a rotatable operating member 64 having an impact member 65 adapted to impact with the cam ring 66 provided on the arms 67 of the impact member, these parts being similar in construction to the impact device shown in Fig. 1, although, of course, other suitable and equivalent means may be employed for imparting slow rotational movements to the sprinkling member as the water flows up through the water casing.

In this form of construction the entire water casing or water chamber is movable vertically within the supporting housing portion 52 when the water is turned on, so that the water casing 56 is substantially above the bottom of the housing portion 52, as shown in Fig. 4, when the device is in operation. When no water is being supplied to the sprinkler the water casing 56 is at or near the bottom of the housing portion 52. The parts are so arranged and designed that the impacts imparted to the sprinkling member will cause it to rotate slowly, even though there is some slight reaction tendency tending to move the sprinkling member in an opposite direction and resulting from the reaction of the water as it flows through the inclined inlet openings 62 and 63 into the water chamber. The entire water chamber 56 is removable with the top piece 50 of the supporting housing when the latter is disconnected and withdrawn from the supporting housing portion 52 to provide access to the inside of the housing portion 52 for cleaning purposes. This operation is effected without disturbing the grass or the ground around the sprinkler.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A sprinkler comprising a rotatable sprinkling member having a water passage therein and having a nozzle connected to said

water passage for directing a stream of water laterally of said sprinkling member, a supporting housing upon which said sprinkling member is normally located in retracted 5 position, said sprinkling member being constructed to be moved during sprinkling operation by the pressure of the water to an extended operating position with the nozzle above the top of the housing portion, a water casing enclosed by said housing portion and in communication with said water passage, and means within said water casing actuated by the movement of the water therein and having impact engagement directly 10 with said sprinkling member to impart slow rotational movement to said sprinkling member.

2. A sprinkler comprising a rotatable sprinkling member having a water passage 20 therein and having a nozzle connected to said water passage, a supporting housing within which said sprinkling member is normally located in retracted position having a water inlet opening at the bottom thereof and having 25 a bearing portion rotatably mounting said sprinkling member, said sprinkling member being constructed to be moved during sprinkling operation by the pressure of the water to an extended operating position, 30 a water casing within said housing and in communication with said water passage, and means within said water casing rotated by the movement of the water therein and having 35 momentum engagement with said sprinkling member to impart slow rotational movement to said sprinkling member.

3. A sprinkler of the class described comprising a rotatable sprinkling member having a water passage therein, a sprinkling 40 nozzle on said sprinkling member and connected to said water passage, a cup-shaped supporting housing portion on which said sprinkling member is normally located in retracted position with the top of the sprinkling member substantially flush with the 45 top of the cup-shaped supporting housing, said sprinkling member being constructed to be moved during sprinkling operation by the passage of water to an extended operating position, a water casing within said supporting housing portion, to which the said water passage is connected, means for supplying water to said water casing, and means within said water casing actuated by the 50 movement of the water therein and having impact engagement with said sprinkling member to impart slow rotational movement to said sprinkling member.

4. A sprinkler of the class described, comprising a lower housing portion and a sprinkling device supported thereon and including a water casing in said housing portion, and also including a sprinkling member rotatable by the flow of water through the 55 sprinkler to which said water casing is con-

nected and means rotatably supporting said sprinkling member and detachably connecting said sprinkling device to the upper part of said housing portion so the sprinkling device together with the water casing is removable upwardly from the housing portion. 70

5. A sprinkler of the class described, comprising a lower housing portion and a sprinkling device supported thereon and including a rotatable sprinkling member, a partition wall detachably supported within said housing portion, a water chamber within said housing portion the bottom thereof being formed by said partition wall, and means operably connecting the partition wall, the 75 top of the housing portion, and the sprinkling member, and means within said water chamber for rotating said sprinkling member.

6. A sprinkler of the class described, comprising a sprinkling member, a supporting top housing piece, a cup-shaped supporting housing portion detachably connected to said housing piece, a partition wall within said housing portion having a water passage for 80 supplying water above said partition wall, means connecting said partition wall to said housing piece so that it is removable with said housing piece through the top of said housing portion, and means above said partition wall for causing the constant rotation of 85 said sprinkling member during the flow of water through said water passage.

7. A sprinkler of the class described, comprising a rotatable sprinkling member having a water passage therein, a sprinkling nozzle on said sprinkling member and connected to said water passage, a supporting top housing piece within which said sprinkling member is normally located in retracted position, 90 a cup-shaped supporting housing portion detachably connected at its upper end to said housing piece, said sprinkling member being constructed to be moved during sprinkling operation by the pressure of the water to an extended operating position with the sprinkling nozzle above the top of said housing piece, a partition wall within said housing portion having a water passage for supplying 95 water above said partition wall, means connecting said partition wall to said housing piece so that it is removable with said housing piece through the top of said housing portion, and means above said partition wall 100 in said water casing and actuated by the passage of water therethrough to impart slow rotational movements to said sprinkling member.

8. A sprinkler of the class described, comprising a rotatable sprinkling member having a water passage therein, a sprinkling nozzle on said sprinkling member and connected to said water passage, a top housing piece within which said sprinkling member is normally located in retracted position with the 105 110 115 120 125 130

top of said sprinkling member substantially flush with the top of said housing piece, said sprinkling member being constructed to be moved during sprinkling operation by the pressure of the water to an extended operating position with the sprinkling nozzle above the top of said housing piece, a cup-shaped supporting housing portion extending from said housing piece and detachably connected therewith, means for detachably securing said housing piece to said housing portion, said housing portion having a water inlet adjacent its lower end, a wall above said water inlet, said wall having water inlet means, means above said wall for imparting controlled rotation to said sprinkling member, and means connecting said wall to said housing piece, whereby said wall is removable with said housing piece from said housing portion.

9. A sprinkler of the class described, comprising a rotatable sprinkling member having a water passage therein, a sprinkling nozzle on said sprinkling member and connected to said water passage, a top housing piece within which said sprinkling member is normally located in retracted position with the top of said sprinkling member substantially flush with the top of said housing piece, said sprinkling member being constructed to be moved during sprinkling operation by the pressure of the water to an extended operating position with the sprinkling nozzle above the top of said housing piece, a cup-shaped supporting housing portion extending substantially to the top of said housing piece and detachably connected therewith, means accessible from the top of said sprinkler for detachably securing said housing piece to said housing portion, said housing portion having a water inlet adjacent its lower end, a wall above said water inlet, said wall having water inlet means, means above said wall for imparting controlled rotation to said sprinkling member, and means connecting said wall to said housing piece, whereby said wall is removable with said housing piece from said housing portion.

In testimony whereof we hereto affix our signatures.

WALTER H. COLES.
BERT J. NELSON.
